Arthur J. Do.
Attorney

UNITED STATES PATENT OFFICE.

ADELARD E. RAVENELLE, OF NORWICH, CONNECTICUT.

SHUTTLE EYE.

Application filed December 19, 1921. Serial No. 523,495.

To all whom it may concern:

Be it known that I, ADELARD E. RAVENELLE, a citizen of the United States, residing at Norwich, in the county of New London and State of Connecticut, have invented certain new and useful Improvements in a Shuttle Eye; and I do hereby declare the following to be a full, clear, and exact description of the invention, such as will enable others skilled in the art to which it appertains to make and use the same.

The object of the invention is to provide an improved eye for shuttles whereby the tendency of the filler yarn to catch under the eye may be prevented while the eye is securely anchored in position and serves to hold the yarn out of contact with the bottom of the shuttle or the material forming the body of the shuttle adjacent to the eye, where it is subject to abrasion by which it is caused to catch in the eye; and with this object in view the invention consists in a construction and arrangement of parts of which a preferred embodiment is shown in the drawing, where-

25 in:-

Figure 1 is a top plan view of a fragmentary portion of a shuttle provided with an eye constructed in accordance with my invention;

30 Figure 2 is a view in side elevation;

Figure 3 is a sectional view taken on the plane indicated by the line 3—3 of Figure 1, and

Figure 4 is a detailed perspective view of 35 the eye.

The eye of which the body portion 10 is of approximately the construction conventionally used in this connection is provided adjacent to one side of the slot 11 with a 40 longitudinally extended lug 12 which is cross sectionally rounded on its inner surface to form a smooth running and bearing surface for the yarn, and which is sharpened at its

extremity as indicated at 13 to engage the material of the shuttle body 14 to hold the 45 eye rigidly in place against turning movement. The wall of the eye adjacent to the slot is thickened as shown at 15 as in the ordinary practice but the inner end of this thickened portion of the wall preferably 50 overlaps or extends beyond the corresponding end of the lug and the edge of the eye of which the lug is an extension to form a slight projecting lip 16.

In practice the construction indicated 55 serves to protect the yarn by preventing it from coming in contact with the bottom of the opening or cavity in the shuttle where it is subject to being threaded or roughed so that the lint or fibres are subject to catching 60 in the eye and interfering with the proper feeding of the filler. The rounded inner surface of the lug serves to guide the yarn into the eye without the liability of frictional resistance as in the ordinary practice. 65

Having thus described the invention, what I claim is:-

A shuttle eye having a longitudinally extending anchoring lug, said anchoring lug having a transversely rounded inner surface, 70 said lug extending from said eye at one edge of the thread receiving slot thereof and being of a height sufficient to overlie the lower edge of the throat leading to the bobbin of a shuttle, and said lug being of substantial 75 length and having its extremity sharpened to form an edge adapted to be driven into the wood of the shuttle to retain the eye in place.

In testimony whereof I affix my signature 80 in presence of two witnesses.

A. E. RAVENELLE.
